[57] CLAIM

The ornamental design for a combined escutcheon and power switch, as shown and described.

DESCRIPTION

FIG. 1 is a top plan view of a combined escutcheon and power switch showing our new design;

FIG. 2 is a left side elevational view thereof;

FIG. 3 is a front elevational view thereof;

FIG. 4 is a right side elevational view thereof;

FIG. 5 is a bottom plan view thereof;

FIG. 6 is a rear elevational view thereof;

FIG. 7 is a perspective view thereof.
The broken line showing of the switch housing in FIGS. 1-5 and 7 is for illustrative purposes only.

FIG. 1
